United States Patent Office

Des. 229,757

Patented Jan. 1, 1974

229,757

TELEPHONE MESSAGE HOLDER

Robert S. Hansen, 151 Glenwood Court,
Santa Rosa, Calif. 95404

Filed Feb. 5, 1973, Ser. No. 329,630

Term of patent 14 years

Int. Cl. D14—03

U.S. Cl. D26—14 A

FIG. 1

FIG. 3

FIG. 2

FIG. 4

FIG. 5

FIG. 1 is an isometric view of a telephone message holder embodying my new design, with a telephone being shown in broken lines for illustrative purpose only.

FIG. 2 is an elevational view of the left side of the telephone message holder, as viewed in FIG. 1.

FIG. 3 is a top plan view of the telephone message holder shown in FIG. 1.

FIG. 4 is a bottom plane view of the telephone message holder shown in FIG. 1.

FIG. 5 is a front elevational view of the telephone message holder shown in FIG. 1.

I claim:

The ornamental design for a telephone message holder, as shown and described.
